W. T. WHITAKER.
MOP HOLDER.
FILED JUNE 11, 1921.

FIG. 3.

INVENTOR

William T. Whitaker.

BY
Frank Bussler
ATTORNEY.

WITNESS:

Bob Pritchel.

UNITED STATES PATENT OFFICE.

WILLIAM T. WHITAKER, OF ELKINS PARK, PENNSYLVANIA.

MOP HOLDER.

Application filed June 11, 1921. Serial No. 476,796.

To all whom it may concern:

Be it known that I, WILLIAM T. WHITAKER, a citizen of the United States, residing at Elkins Park, county of Montgomery and 5 State of Pennsylvania, have invented a new and useful Improvement in Mop Holders, of which the following is a full, clear, and exact description, reference being had to the accompanying drawings, which form a part 10 of this specification.

My invention relates to an improvement in mop holders and more especially to means for removably securing a mop to its handle.

The object of my invention is to provide 15 means for securing a mop to its handle, so constructed as to accommodate mops of various sizes and any given mop irrespective of its lack of uniformity in size.

A further object of my invention is to 20 provide means for securing a mop to its handle, which will permit of the mop being readily attached and removed, and which will hold the mop securely without risk of damage to it.

25 By virtue of my invention I provide a mop handle equipped with means for attaching a mop, which is highly efficient, will accommodate itself to mops of varying sizes and lacking in uniformity, and at the same 30 time which will be simple in manipulation and inexpensive to manufacture.

Having now briefly described the nature 35 of my invention, I will proceed to describe a preferred embodiment thereof in detail with reference to the accompanying drawings, in which—

Figure 1 is a front elevation of a mop handle embodying my invention.

Figure 2 is a side elevation of the subject 40 of Figure 1.

Figure 3 is a plan view of the subject of Figure 1.

α indicates a handle, preferably of wood, fitted into a socket member b , extending 45 from the apex of a triangular base member c . In opposite sides of the socket member b are formed bosses d , which extend at an angle to the axis of the handle and which are bored for the reception of rods e . The rods e are 50 threaded at one end for the reception of wing nuts f , and extend through the bosses d in a direction parallel to the sides of the base, respectively, the free end portions g extending oppositely beneath the base toward, but 55 not into contact with each other. The free end

portions g are bevelled at their inner ends as shown in Fig. 1, and the rods are off-set between their ends as at h , to bring the free end portions into line with each other, centrally beneath the base. 60

It will now be noted that when the wing nuts on the rods e are tightened the free end portions of the rods are drawn toward each other and upward toward the bottom of the base to the position shown in Figure 1. 65 Conversely as the wing nuts are loosened the rods e are let out and the free end portions are moved away from each other and away from the bottom of the base as one of which is shown in broken lines Fig. 1. 70

It will now be apparent that by inverting the base, loosening up the wing nuts, letting out the rods e and turning their free end portions to opposite sides, a mop may be 75 laid over the bottom of the base. To secure the mop in position it is only necessary to turn the free end portions of rods e back to overlie the mop and tighten up the wing nuts, which will draw the free ends g of the rods toward each other and toward the base 80 thus securing the mop, which is then ready for use.

It will be noted that mops of a variety of different sizes may be accommodated by more or less drawing in of the rods e and 85 that in the event that any given mop is not uniform in size one or the other of rods e may be drawn in more or less to accommodate any lack of uniformity. It will also be noted that the bevelled ends of the rods e 90 will not cut into the strands of the mop, but will rather push the strands aside as the ends are drawn in.

What I desire to claim and protect by Letters Patent is:

1. A mop holder comprising a base provided with a handle-receiver socket, a pair of members each supported adjacent one end by the base and having a free end portion extending beneath the base and adapted to 100 engage a mop and clamp it to the base, the free end portions being adjustable toward and away from each other and toward and away from the base without changing their angular relationship to the base. 105

2. A mop holder comprising a base provided with a handle receiving socket, a pair of rods, bosses on said base bored for the passage of said rods and extending at an angle to the axis of the handle receiving 110

socket, the upper end portions of said rods being adapted to extend through said bosses, the lower end portions being free and bent back and adapted to extend oppositely beneath and parallel to the bottom of said base, and means whereby the free end portions of said rods may be adjusted toward and away from said base.

3. A mop holder comprising a triangular base provided with a handle receiving socket, bosses formed on opposite sides of said socket and extending parallel to the sides of said base respectively, a pair of rods formed to extend along opposite sides and oppositely along the bottom of said base, said rods extending through said bosses and being oppositely offset intermediate their ends to bring them in line beneath the base, and means to adjustably secure said rods to the base.

4. A mop holder comprising a base provided with a handle receiving socket, bosses formed on opposite sides of said socket, said bosses being bored at an angle to the axis of

said socket, a pair of rods formed to extend 25 along opposite sides and oppositely along the bottom of said base, the opposing ends thereof being bevelled, said rods extending through said bosses and being oppositely offset intermediate their ends to bring them 30 in line beneath the base, and means to adjustably secure said rods to the base.

5. A mop holder comprising a base provided with a handle receiving socket, a pair of rods carried by the base and having their 35 free ends adapted to extend oppositely beneath said base in alignment, and means whereby the free ends of said rods may be moved toward and away from the base and simultaneously toward and away from each 40 other.

In testimony of which invention I have hereunto set my hand, at Philadelphia, on this 9th day of June, 1921.

WILLIAM T. WHITAKER.

Witness:

ERNEST H. MANCKE.
